(57) **CLAIM**

The ornamental design for a side view type light emitting diode, as shown.

DESCRIPTION

FIG. 1 is a perspective view of the side view type light emitting diode, showing our new design;

FIG. 2 is a front elevational view of the side view type light emitting diode of FIG. 1;

FIG. 3 is a rear elevational view of the side view type light emitting diode of FIG. 1;

FIG. 4 is a left side elevational view of the side view type light emitting diode of FIG. 1;

FIG. 5 is a right side elevational view of the side view type light emitting diode of FIG. 1;

FIG. 6 is a top plan view of the side view type light emitting diode of FIG. 1;

FIG. 7 is a bottom plan view of the side view type light emitting diode of FIG. 1;

FIG. 8 is a rear three-dimensional view of the side view type light emitting diode of FIG. 1; and,

FIG. 9 is perspective view of the side view type light emitting diode, a transparent part thereof being separated from a main body thereof.
